SPRING MOUNTING

Gerhard Spiller, Brooklyn, N. Y., assignor to
Bendix Aviation Corporation, South Bend, Ind.,
a corporation of Delaware

Application March 14, 1934, Serial No. 715,569

4 Claims. (Cl. 33—222)

The present invention relates to spring mountings for instruments, particularly for the indicating or recording elements of indicators and/or recorders.

5 One of the objects of the invention is to provide a novel support for an element such as a compass card of a magnetic compass or a recording pen or pencil of a recorder, for example, whereby vibrations in a vertical plane are prevented from being transmitted to such an ele- 10

15 Another object is to provide, in combination with a compass card having a pivot pin mounted on a vertically supported bearing, novel means for preventing transmission of vertical vibrations to the card particularly when the compass is mounted on an aircraft, said means serving also as the sole support for the card on the pivot pin.

20 A further object is to provide a novel spring mounting for a compass card having a pivot pin or for a recording pen of a recorder, whereby vertical vibrations of the card or pen arm are prevented and whereby the pivot pin or recording pen may be readily removed from the mount- 25

25 ing for inspection or replacement thereof.

Still another object is to provide a novel shock-absorbing spring for sensitive elements of delicate instruments, as for a compass card of a compass or for a recording pen of a recorder, 30 and comprising a strip of spring material bent up so that its ends come substantially adjacent each other in a horizontal plane and are secured to the card or to the pen arm, either directly or indirectly, and so that the body of the spring 35 extends upwardly from each end to form a resilient bridge between the upwardly extending portions and substantially parallel to the plane of the adjacent ends whereby a pivot pin or recording pen may be inserted to project upwardly 40 between the adjacent ends of the spring and bear against the bridge, thus providing a resilient abutment for the pin or pen.

45 The above and other objects and advantages of the invention will appear more fully hereinafter from a consideration of the detailed description which follows, taken together with the accompanying drawing wherein two embodiments and two applications of the invention are illustrated. It is to be expressly understood, however, 50 that the drawing is for the purpose of illustration and description only and is not to be construed as defining the limits of the invention, reference being had to the appended claims for this purpose.

55 In the drawing wherein like reference char-

acters refer to like parts throughout the several views,

Fig. 1 is a front elevation, partly in section, 5 of one embodiment of the invention shown applied to a card of a magnetic compass;

Fig. 2 is a similar view of a like embodiment as applied to a recorder;

Fig. 3 is a partial view in section of another embodiment shown applied to a compass card;

Fig. 4 is a detailed perspective view of the em- 10 bodiment shown in Fig. 3; and

Fig. 5 is a detailed view of another embodiment which may be applied to a compass card or to a recorder.

Referring to the drawing, and more particularly to Fig. 1, the invention is shown in one form applied to a compass card 6 which has suspended therefrom a pair of magnets 7 and 8 by means of members 9 and 10 carried by the card. The card is adapted to be carried on pivot post 11 at the 20 top of which is provided a cup-shaped jewel bearing 12 into which a pivot pin 13 is adapted to be inserted. Secured to the card 6 is a guard member 14 to prevent displacement of the pivot pin 13 from the bearing 12. Means are now pro- 25 vided for resiliently supporting the card 6 on the bearing 12 in order to prevent vertical vibrations from being transmitted to the card from the pivot post 11, particularly when the compass in which the card is embodied is carried on a ve- 30 hicle such as an airplane which is subject to engine vibrations. In the form shown, said means comprise a spring 15 which is formed from a strip of spring material and bent up so that the ends 16 and 17 thereof are substantially adjacent 35 each other in a horizontal plane but not completely abutting each other and so that the body of the spring extends upwardly from the ends 16 and 17, as shown at 18 and 19, to form a resilient bridge 20 between the upwardly extending portions 18 and 19 and substantially parallel to the plane of the ends 16 and 17 whereby the pivot pin 13 may project upwardly between the adjacent ends 16 40 and 17 of the spring so as to bear against the bridge 20, thus providing a resilient abutment 45 for said pivot pin. Substantially mid-way between the ends of the bridge 20 there is provided an indentation 21 whereby the pivot pin 13 may be readily centered with respect thereto and the upper end of which is adapted to be seated there- 50 in. In order to provide for variation in the resiliency of the bridge 20, the upwardly extending portions 18 and 19 may be bent downwardly to form loops 22 and 23 before the bridge 20 is formed. By bending the loops 22 and 23 toward 55

each other the resiliency of the bridge 20 may be decreased, i. e., the bridge 20 becomes more rigid. In this embodiment the ends 16 and 17 of the spring are secured to an enlarged annular flat portion or head 24 of a hollow, preferably cylindrical, member 25 through which the pin 13 is adapted to extend and which is pressed into a hollow cylindrical portion 26 secured to or formed integrally with the guard 14. Thus by the rigid connection between the tubular member 25 and the tubular portion 26 and by the connection of the ends 16 and 17 of the spring to the head 24, the resilient spring mounting thus formed becomes an integral part of the compass card 6.

15 The pivot pin 13 is provided with an enlarged head 27 to prevent it from passing through the tubular member 25 but which is adapted to move freely within said member. Thus it will be seen that as the pivot pin 13 rests on the jewel bearing 12 it supports the entire compass card structure by means of the novel spring 15 at the indentation 21 formed in the bridge 20. Consequently, any vibration of the pivot post 11 in a vertical direction is absorbed through the pivot pin 13 by the bridge 20 of the spring. If it be desired to replace the pivot pin 13, all that is necessary is to lift the bridge 20 slightly and move it a little to one side or the other of the pin thereby making the latter accessible for removal from the tubular member 25.

Referring to Fig. 2, there is shown an embodiment of the invention like that in Fig. 1 but applied to a recording instrument consisting generally of some sensitive element (not shown) responsive to changes in conditions and enclosed in a housing 28 and having a recording pen arm 29 projecting from said housing 28. The end of the pen arm 29 is provided with a vertical tubular portion 30 into which the tubular member 25 of the novel spring mounting is inserted and to which it is secured. Within the tubular member 25 is guided a recording pen 31 the upper end of which abuts against the bridge 20 in the same manner as the pivot pin 13 of the compass card shown in Fig. 1. The pin cooperates with a recording chart 32 carried by a drum 33 which is rotatable about its axis 34 by some suitable mechanism such, for example, as a clock work (not shown) whereby a time record may be obtained on the chart 32 of the changes of the conditions as determined by the sensitive element located within the housing 28. The entire recording mechanism is carried on a suitable panel 34 and thus any vibration of the panel which may be transmitted to the drum 33 is prevented from being transmitted back to the recording pen arm 29 through the pen 31 by means of the bridge 20 of the novel spring mounting.

Referring to Fig. 3, there is shown an embodiment similar to that shown in Fig. 1 except that the ends 16 and 17 of the spring 15 are connected directly to the tubular portion 26 of the guide 14 which is carried by the compass card 6.

If desired, the loops 22 and 23 of the spring 15, as shown in Figs. 1, 2, 3 and 4 may be dispensed with and the spring may take the form shown in Fig. 5 wherein the bridge 20 extends directly across the upwardly extending portions 18 and 19, the latter being slightly shorter than as shown in Figs. 1, 2, 3 and 4.

There is thus provided a novel resilient mounting for sensitive elements of delicate instruments, which is relatively simple and inexpensive and which consists of a small strip of spring material

bent up in a novel manner to provide a resilient support whereby vertical vibrations are absorbed by the spring and prevented from being transmitted to the element with which they are associated.

Although only two embodiments of the invention have been illustrated and described other changes in the shape and form of the spring, which will now appear to those skilled in the art, may be made without departing from the scope of the invention. Reference is, therefore, to be had to the appended claims for a definition of the limits of the invention.

What is claimed is:

1. A spring mounting comprising a tubular member, a strip of spring material bent down so that its ends are substantially adjacent each other in a horizontal plane and secured to the tubular member at diametrically opposite sides of its upper end and so that the body of the strip extends upwardly from each of its ends to form a resilient bridge between said upwardly extending portions and substantially parallel to the plane of the adjacent ends, and an elongated member extending slidably through the tubular member and having its upper end abutting the resilient bridge of the strip whereby said strip constitutes a shock absorber for any device which may be connected to the tubular member.

2. A spring mounting for a compass card, comprising a tubular member adapted to be secured to the center of the card perpendicularly to the plane of the card, a strip of spring material bent down so that its ends are substantially adjacent each other in a horizontal plane and secured to the tubular member at opposite sides thereof and so that the body of the strip extends upwardly from each of its ends to form a resilient bridge between the upwardly extending portions, and a pivot pin on which the card is adapted to be supported, said pin extending slidably through said tubular member and having its upper end abutting the resilient bridge of the strip.

3. A spring mounting for a compass card, comprising an elongated hollow member adapted to be secured to the center of the card perpendicularly to the plane of said card, a strip of spring material bent down so that its ends are substantially adjacent each other in a horizontal plane and secured to the hollow member on opposite sides thereof and so that the body of the strip extends upwardly from each of its ends to form a resilient bridge over one end of the hollow member and between the upwardly extending portions, and a pivot pin on which the card is adapted to be supported, said bridge having an indentation substantially mid-way between the upwardly extending portions and constituting a centering guide for the pin, the latter extending upwardly through the hollow member and having its upper end abutting the resilient bridge of the strip at said indentation.

4. A spring mounting for a compass card, comprising a pivot passing through the center of the card and adapted for relative longitudinal movement with respect to said card, and a substantially flat spring having its ends bent upon itself and anchored on opposite sides of the opening from which said pivot projects so that the body of the spring is disposed over and on the upper end of said pivot whereby said spring constitutes the sole support for the card on said pivot.
